2 SHEETS—SHEET 2.

UNITED STATES PATENT OFFICE.

EUGENE HOLT AND LAFAYETTE HOLT, OF BURLINGTON, NORTH CAROLINA.

BEAM DYEING-MACHINE.

1,269,934.

Specification of Letters Patent. Patented June 18, 1918.

Application filed July 1, 1915. Serial No. 37,546.

To all whom it may concern:

Be it known that we, EUGENE HOLT and LAFAYETTE HOLT, citizens of the United States, and residents of Burlington, in the county of Alamance and State of North Carolina, have invented certain new and useful Improvements in Beam Dyeing-Machines; and we do hereby declare the following to be a full, clear, and exact description of the invention, such as will enable others skilled in the art to which it appertains to make and use the same.

This invention relates to an improved apparatus for the treatment of yarns, or other similar materials, in the operation of cleaning, boiling, bleaching, dyeing, oxidizing, fixing, developing, etc.; and further, this invention relates more particularly to that type of apparatus recognized by those versed in the art as a beam dyeing machine, wherein the material to be taken under treatment is first warped or wound upon a yarn beam and is thence placed in the machine for treatment, from whence it is taken for treatment by the sizer or slasher.

One of the most important objects of the present invention is to provide a machine of the above-mentioned type wherein the treatment of the yarn, or other material, is performed in rapidly succeeding steps, thereby insuring a uniformly dyed product, free from spots or other discolorations.

A further very important object of our invention resides in the provision of an apparatus of this class wherein the yarn is immersed by submerging the beam by the introduction of the dye-stuff at the bottom of a vat containing a vertical beam wound with yarn, the dye-stuff being fed in both from within and without the beam.

A still further important object of our invention resides in the manner of expelling the dye-stuff from the vat and beam, and simultaneously producing oxidation of the dye-stuff, impregnating the beam as the main body of dyestuff recedes, thereby insuring a uniform oxidation of the dye-stuff impregnating the yarn.

It may be here mentioned that while this apparatus is adapted for the many treatments hereinbefore referred to, it is more particularly adapted to carry out the steps of the process set forth in our co-pending application filed in the United States Patent Office the 29th day of May, 1915, and bear-

ing the Serial Number 31275, and entitled "A process of dyeing yarn."

With the above and other objects in view, the invention consists in the construction and combination of parts illustrated in the accompanying drawings and hereinafter specifically described, it being understood that various changes in the form, proportions, and other minor details of construction, may be resorted to in actual practice, without departing from the spirit and scope of the invention.

In the drawings, which, as above stated, are typical of one form of the apparatus, and particularly illustrate a form which we have found in actual practice to give good results:

Figure 1 is a central section elevation view through the apparatus.

Fig. 2 is a transverse section through the apparatus; the plane of this section being the line 2-2 of Fig. 1.

Fig. 3 is a plan view of a portion of the cover locking mechanism.

Fig. 4 is a cross-cut section view of a portion of the wall of the reticulated beam used in connection with this apparatus.

Fig. 5 is a diagrammatic perspective view illustrating the circulating system.

In detail:

The apparatus illustrated comprises the vertical vat 1 of cylindrical form to receive and contain a beam 2 during the treatment operation, and it is upon this beam that the yarn, or other material, undergoing treatment is warped or wound, as indicated by the dotted lines at 3.

The beam 2, preferably of that type illustrated in our co-pending application filed in the United States Patent Office March 3, 1915, and bearing the Serial Number 11727, this application being entitled "A yarn beam," principally consists of a reticulated body 4 having ends 5 and 6, the lower one being apertured as at 7 to admit the dye-stuff to the interior of the beam, whereas the upper one is provided with an air relief cock 8 for purposes to be hereinafter set forth.

The lower end member 5 of the beam 2 must make a steam tight joint with the bottom of the vat 1 and must be positioned directly over a port 9 in the bottom of the vat. In order to hold the beam 2 in this position a cross bar 10 is provided which engages

with the upper end of the vat and carries a centering pin 11 threaded therein and for engagement with the center rod 12 of the beam when the pin is screwed down by means of the hand-wheel 13.

6 The cover for the cylindrical vat 1 is of that type illustrated in the pending application of Lafayette Holt, filed in the United States Patent Office June 10, 1915, and bearing the Serial Number 33337, said application being entitled "A tank closure or cover." This cover comprises essentially a main cover 14 and a superposed rotatable plate 15 provided with angular slots which, upon the 10 rotation of the plate 15, simultaneously move a plurality of locking members into and out of a locking position as the case may be. The locking members are illustrated at 16 and may be tightened in the locking position by hand-wheels 17.

20 At the bottom, the vat 1, as before stated, is ported at 9 and this port communicates with the interior of the beam 2 through apertures 7 in the bottom end thereof. The bottom of the vat 1 is also apertured exteriorly of the beam as at 18 to communicate with the vat outside of the beam 2.

25 The circulation system comprises a tank 19 for containing a quantity of dye-stuff in fluid form, and leading from the bottom of this tank is a pipe 20 which connects at 21 with the suction end of a centrifugal pump 22, and further has a branch 23 leading to a water supply. The branch 23 is controlled 30 by a valve 24 and the outlet 20 is controlled by a valve 25. Thus either water or fluid dye-stuff may be fed to the pump 22.

35 In order to drain the vat 1 and tank 19, a valve 26 is located adjacent to a T 27 in the pipe 20 and is in connection with the latter, and a pipe 28 leads therefrom to the sewer. Immediately adjacent the T 27 and between the pump and said T is located a valve 29, and if this valve 29 is closed and valves 26 40 and 25 are opened, the tank 19 may be drained. From the discharge end of the pump 22 leads a pipe 30 which has its outlet end 31 turned into the tank 19. In the pipe 30 are located two valves 32 and 33, the 45 former being immediately adjacent the pump discharge outlet, and the latter adjacent the outlet of the pipe 30. Intermediate of the two valves 32 and 33 are located two T's 34 and 35 which lead to valves 36 and 37, connecting with pipes 38 and 39, the former entering the port 9 and communicating through apertures 7 with the interior of the beam 2, while the latter enters the port 18 and is in communication with the vat 1 exteriorly of the beam 2. In connection with the two pipes 38 and 39 are other pipes 40 and 41, respectively, which lead to valves 42 and 43 connecting with T's 44 and 45 in the pipe 20 and located between T 27 and 50 valve 25.

55 By this arrangement the fluid dye-stuff contained within the tank 19 may be circulated from without the beam 2 to within the beam, or vice versa. For instance, by opening the valves 25, 29, 32, 36 and 37, the dye-stuff is drawn from the tank 19 by the pump 22, is discharged through pipes 38 and 39 into the interior of the beam 2 and also into the interior of the vat exteriorly of the beam. Thus the beam and vat may be simultaneously filled. In order to relieve the air pressure from within the beam 2 which, by reason of the said beam being heavily wound or warped with yarn, accrues therein, an air cock 8 is provided in the top end 6 of the beam. Before placing the cover 14 in position, the tank and beam are filled in the manner above set forth, and the air cock 8 is then closed, consequently no air remains within the beam. The cover 14 is then placed in 60 position and to continue operations the dye-stuff is circulated from without to within the beam by closing all of the valves and then opening valves 42, 29, 32 and 37. After this circulation or agitated flow of liquid has 65 taken place for a suitable length of time, these valves are closed and a flow of dye-stuff is induced from within to without the beam by opening valves 43, 29, 32 and 36. It will thus be seen that by suitably controlling the valves above-mentioned the fluid dye-stuff or other treating agents may be 70 circulated in either direction through the beam, thereby thoroughly impregnating the 75 yarn wound thereon.

80 In using oxidizable dyes such as indigo dye liquor or stuff, it is found to be desirable to follow the dye liquor up with a volume of air; as the liquid recedes from the 85 yarn or is withdrawn from the apparatus. Unless this is done the yarn will be spotted, 90 since it is the air that completes the coloring of the yarn by chemical oxidation of the dye liquor absorbed by the yarn. In 95 order to accomplish this, an air inlet 46 is 100 provided adjacent the top of the vat 1, and connects with an air supply 47 which also has a branch 48 entering the pipe 30 between T 35 and valve 33. If air be admitted at the inlet 46 the air will course 105 through the beam 2 and out the bottom thereof driving the unabsorbed dye liquor with it and following up the receding dye liquor by the oxidation of the dye liquor 110 impregnating the yarn, thereby insuring an even oxidation through and through the 115 yarn and a consequent uniform spotless coloring of the yarn. By the arrangement of the air pipe system it is also evident that 120 by manipulating the battery of valves in 125 connection with the circulation system, the air may be circulated in the same manner as the dye-stuff. Also by reason of the water inlet 23 at the end of pipe 20, wash water 130 may be circulated in the same manner.

as the dye-stuff. Furthermore, it is known to be desirable at certain stages of the dyeing process, to circulate steam within the vat or beam and to provide for this a steam inlet 49 is provided which is tapped into the pipe 30 between T's 34 and 35, and still further it is known to be desirable during certain stages of the dyeing process to utilize dry heat and for this purpose a heating coil 50 surrounds the beam at the bottom thereof and is connected with a steam supply 51 and discharges through the open end 52.

It will be seen from the apparatus hereinbefore set forth that thorough treatment of the yarn or other material wound on the beam 2, with a cleansing agent, bleaching agent, or dyeing agent, may be accomplished by arranging for the circulation of the various agents and accessory agents such as steam and air, in various directions through the yarn, and by such circulations an agitation is produced in the medium circulated which keeps all solid matters suspended in the solution. The particular utility in carrying out indigo dyeing wherein the dye is oxidized, lies in the fact that the dye-stuff to be oxidized is oxidized by the agent which, under pressure, drives the superfluous dye-stuff out of the material and out of the vat and beam, following up the dye-stuff as it recedes.

From the foregoing description in connection with the accompanying drawings, it will be evident that an apparatus admirably suited for the purposes herein set forth has been constructed. Also it will be apparent that a battery of vats may be ar-

ranged to be operated in connection with a single circulatory system and battery of valves such as that indicated, and also that a plurality of beams may be arranged for treatment in a single vat.

We claim:

1. Yarn treating apparatus including a closed vat, a perforated beam mounted therein for holding a quantity of warped or wound yarn, a liquid circulatory system for circulating treating agents from within to without said beam and vice versa, means for introducing compressed air above the surface of the liquid level in the vat for simultaneously forcing the treating agents from the vat and for oxidizing the treating agents upon the yarn as the treating agents escape from the vat, and means for introducing compressed air into the bottom of the beam.

2. Yarn treating apparatus including a closed vat, a perforated beam mounted therein for holding a quantity of warped or wound yarn, a liquid circulatory system for filling the vat and beam, means for reversing the flow of liquid in the circulatory system, and independent means for introducing compressed air into the top of the vat and the bottom of the beam.

In testimony whereof, we have signed this specification in the presence of two subscribing witnesses.
